UNITED STATES PATENT OFFICE.

HARRY S. HART, OF CHICAGO, ILLINOIS, ASSIGNOR TO NATIONAL DUMP CAR CO., OF CHICAGO, ILLINOIS, A CORPORATION OF MAINE.

DOOR-OPERATING MECHANISM.

1,318,444.

Specification of Letters Patent.

Patented Oct. 14, 1919.

Application filed February 21, 1919. Serial No. 278,408.

To all whom it may concern:

Be it known that I, HARRY S. HART, a citizen of the United States, residing at Chicago, in the county of Cook and State of Illinois, have invented certain new and useful Improvements in Door-Operating Mechanism, of which the following is a specification.

This invention relates to door operating mechanism particularly in connection with general service cars.

The objects of the invention are to provide a simple and efficient door operating mechanism which is positive in its action, so arranged that no strain is placed upon the mechanism tending to distort it, thus minimizing repairs; to provide a device which can be easily operated by the class of lever usually employed for such purpose; and to provide an operating device so arranged as to increase the efficiency of the car in unloading.

General service cars, as is well known, have their flat bottoms composed largely of drop doors from which the dumpable loading is discharged. It has been customary in the past to provide operating mechanisms for these doors, by means of which a plurality of the doors can be closed and opened simultaneously. The classes of operating mechanisms, generally speaking, are of two kinds, those which employ a winding shaft connected by chains or flexible elements to the doors, and those in which the shaft placed beneath the doors operates directly to raise the same. The first class of device is open to the objection that, owing to the weight of the doors, the chains or flexible elements connecting the doors to the shaft are apt to stretch or kink unequally so that some of the doors may not be fully closed, making it impossible to transfer the load from the chain to the shaft through suitable devices usually employed. Cars having these chain and shaft operated doors are open to the further objection that the chains are in the path of the outgoing load as it is discharged, thus hindering the free flow of material from the car. Cars of the second class, that is, those employing the shaft as the direct operating member for the doors, while free from the last-named objection are apt to become defective because of the torsional strains imposed upon the shaft in closing the doors. These shafts

extend approximately one-half the length of the car and are operated from the end of the car by rolling the shaft back and forth beneath the doors. The shaft ends farthest from the ends of the car, owing to the torsional strain upon the shaft, will sometimes become distorted so that certain of the doors will not be fully closed. This is especially true if small amounts of material are left upon the doors, requiring the exercise of unusual effort to compel the shaft to move into fully closed position.

My new door operating mechanism disclosed in this application overcomes the objections to both types of mechanism, there being no chains to interfere with the load or become stretched, and there being no strain imposed upon the shaft in moving it under the doors to support them. The closing of the doors by lifting each door singly can be done with less effort, and probably in less time, than a complete section can be raised by the old devices, while the dropping of the doors in sections takes place as formerly.

Another advantage of lifting the doors singly is that the operator sees any objects of material which may be left on the door or underframe requiring cleaning off. When the doors are raised from the end of the car as is now commonly done, it is not always possible to notice these things, the result being that attempts are frequently made to close the doors when particles of coal are interposed between the edge of the door and the adjacent underframe member, thus putting a great strain upon the operating mechanism in attempting to force the doors into fully closed position.

The invention is illustrated on the accompanying sheets of drawings, in which—

Fig. 1 is a fragmentary side elevation of a general service car embodying my invention.

Fig. 2 is a transverse sectional view of the same car showing the door operating mechanism in various positions.

Fig. 3 is a detail view, parts being in section, showing parts of my improved door operating mechanism on a larger scale.

Fig. 4 is a fragmentary bottom plan view of a part of the door operating mechanism; and

Fig. 5 is a fragmentary side elevation of a modified form of general service car em-

bodilying my invention, it being noted that the sides of the car at the ends thereof are provided with side dump doors, bottom dump doors being provided throughout the 5 remaining part of the car.

The various novel features of my invention will be apparent from the following description and drawings, and will be particularly pointed out in the appended 10 claims.

Referring first to Figs. 1 to 4 inclusive, it will be noted that I have shown a general service car having sides 10, ends 11, and a floor composed largely of dump doors 12 which are pivotally connected at their inner ends to the center sill structure 13, the framework of the car including transverse supporting and strengthening members 14 which are provided with stop members 15 upon which the dump doors 12 rest when in an open position.

This invention has to do primarily with the door operating mechanism. Having in mind the disadvantages of door operating devices heretofore employed, and the advantages of this present door operating mechanism as hereinabove set forth, attention is called to the fact that each of the dump doors is raised from an open position into a 20 closed position separately and independently of any other one of the doors. Secured to the bottom of each of the dump doors 12 is a bracket 16 having side walls between which a rivet 17 extends, said rivet being 25 received by an elongated slot 18 formed in one end of a door operating member 19, whereby the door operating member may be moved in and out transversely with respect to the car, for reasons to be mentioned hereinafter. It will be noted also that the width of the slotted end of the member 19 is considerably less than the distance between the side walls of the bracket 16, whereby the 30 operating handle may have considerable side play, the purpose of which will be pointed out later.

Let it be assumed that all of the dump doors 12 are in their open or lowered position as shown at the right hand side of Fig. 2. It will be noted that the operating handle 19 upon each one of these doors is in its outermost position, that is to say, the rivet 17 occupies the innermost end of the slot 18 in the control member 19, this being true as 35 a result of the action of gravity. Each of the doors 12 may be raised individually from its open position, as shown at the right hand side of Fig. 2, into closed position by exerting a lifting movement upon the operating 40 handle 19, and when the door reaches its closed position in each case it may be latched or held temporarily in said closed position by moving the control handle 19 sidewise so that its laterally extending projection or 45 latch portion 20 passes over a receiving lip

21 formed at the bottom of each of a plurality of brackets 22 secured to the frame of the car. At this point, attention is called to the fact that each of the control members 19 intermediate its ends is provided with an 50 offset portion 23, having two cam surfaces 24 and 25 which coöperate with a loop member 26 secured to the underside of each door 12 and through which the control handle 19 extends. Referring particularly to Fig. 4, 55 it is obvious that in order for the latch portion 20 of the control handle 19 to overlie the supporting lip 21, the control handle must move or be moved outwardly, and in such movement the cam portion 25 causes the control handle, during the initial part of its outward movement, to swing laterally away from the supporting lip 21. However, as soon as the peak of the cam is past the control handle 19 may be moved laterally in 60 the opposite direction in order that the latch portion 20 of the handle 19 may overlie the supporting lip 21 for holding the dump door 12 in closed position.

While it is desirable to raise each one of 65 the dump doors individually and to latch each of the dump doors temporarily and individually, as hereinabove set forth, it is desirable to lock a plurality of doors in a more permanent manner simultaneously and to 70 release a plurality of doors simultaneously to permit the dump doors to move into an open position for dumping purposes. To lock a plurality of doors simultaneously after the same have been raised into closed 75 position individually and latched temporarily and individually, I have provided an operating shaft 27 in each quarter of a car, the operating shaft in each quarter controlling all of the dump doors in its section. 80 When the dump doors are in open position, the operating shaft 27 in each case lies outside of the path of movement of said doors as they are moved into closed position. The shaft in each case is moved into a door-supporting position after the doors are raised 85 into closed position, each operating shaft 27 having a lateral movement within inclined slots 28 formed in the frame members 14, each shaft being provided with suitable 90 gears 29 meshing with rack members 30 secured to the frame members 14 at the slots 28. Each operating shaft 27 is provided with an operating lever or handle 31, which is fixed to the shaft and through which the 95 shaft is rolled in under the doors by a continuous movement, as distinguished from the pumping action of the pawl and ratchet levers heretofore used.

Let it be assumed that all of the dump 100 doors 12 have been raised into closed position and are temporarily latched in closed position by the latch portions 20 of the control handles 19 overlying the supporting lips 21. To lock simultaneously in a more per- 105

manent manner all of the dump doors associated with a single shaft, the shaft 27 is given an inward and upward rolling movement by raising the operating lever 31. 5 During the inward movement of the shaft it engages upstanding projections 32, formed on each one of the hand levers 19, forcing said hand levers 19 inwardly toward the longitudinal center of the car, 10 whereby the latched portion is moved out of operative position with respect to the supporting lip 21 in each case, the weight of the doors and the load thereby being transmitted from the supporting lip 21 to the operating shaft 27. During the first part of the 15 rearward movement of the member 19 as it is being actuated by the shaft 27 the outer portion of the handle is given a lateral movement as a result of the cam 24 engaging 20 its coöperating loop member 26 for disengaging the latched portion 20 from the supporting lip 21. However, the control member 19 may return in a lateral movement a predetermined amount after the peak of the 25 cam portion or projection 23 is past. However, it will be noted that with the control lever 19 in its innermost position when the rivet 17 occupies the outer extremity of the slot 18, or, as a matter of fact, when the control member occupies any position excepting its actual latching position, the control member 19 is held out of latching engagement with respect to the supporting lip 21 so that when the shaft 27 is given an outward lateral movement all of the dump doors 12 in that section may be dumped simultaneously.

By means of this door operating mechanism each of the dump doors may be raised 40 into a closed position individually and independently of any other dump door, may be temporarily latched in closed position, then a plurality of the dump doors locked simultaneously in a more permanent manner, 45 the weight of the load and doors being transmitted from the latching means to the normal supporting and operating shaft, and then a plurality of the dump doors released simultaneously for dumping purposes. In 50 this way, each door is given individual attention at the proper time, that is, when it is moved into a closed position, at the same time the use of chains and their accompanying disadvantages are overcome and the distortion of raising shafts likewise is overcome, providing an efficient, simple, and durable construction adapted to meet all of the requirements for successful commercial use.

The arrangement shown in Fig. 5 is substantially the same as that shown in the other figures of the drawings, with the exception, however, that the sides of the car at the ends thereof are provided with side dump doors 33 instead of bottom dump 65 doors at such points, the remaining portion

of the car being provided with a floor having bottom dump doors, as considered in connection with the other figures of the drawings.

There may be various modifications of my invention, and it is my intention to cover all such modifications which do not involve a departure from the spirit and scope of the invention as set forth in the following claims.

I claim:

1. In a general service car having a plurality of doors, means for directly lifting said doors to closed position individually, and means common to a plurality of doors for holding them in closed position.

2. In a general service car having a plurality of doors, means for directly actuating said doors individually in a given direction, and means common to a plurality of doors for holding them in a given position.

3. In a general service car having a plurality of doors, means for holding the doors temporarily in closed position, a movable door operating device, and means for releasing said temporary holding means when the movable door operating device is moved into a supporting position.

4. In a general service car having a dump door, means for locking said door, and other locking means for said door capable of changing the locking connection of the first-mentioned locking means.

5. In a general service car having a pivotally mounted door, means for locking said door in closed position, and other means for locking said door in said position which is capable of moving the first locking means into an unlocking position.

6. In a general service car having a movably mounted door, a locking member carried thereby for locking the door in one position, and other locking means for said door capable of moving the first locking means into an unlocking position.

7. In a general service car having a movably mounted door, locking means carried thereby for coöperating to lock the door in closed position, and locking means for said door carried by a stationary part of the car and having an unlocking action upon the first-mentioned locking means.

8. In a general service car, a movably mounted door, a locking latch carried thereby coöperating to lock the door in closed position, and a shaft supported by a stationary part of the car and movable into a position to support the door in closed position, the locking latch at the same time being moved into an unlocking position.

9. In a general service car having a movably mounted door, a locking latch carried thereby and movable into locking and unlocking positions, and a shaft capable of holding the door in closed position causing

said latch to move from a locking to an unlocking position when the shaft is moved into a supporting position.

10. In a general service car having a movably mounted door, a handle for raising said door into closed position, said handle having a relative movement with respect to said door, whereby it may be moved into a position to lock and unlock the door, and other door operating means operable within the frame of the car for moving the handle from a locking into an unlocking position as the other door operating member is moved into a supporting position.
- 15 11. In a general service car having a movably mounted door, a handle mounted on said door and having relative sidewise and longitudinal movements with respect there-

to, said door being manually closed by movement of said handle, and means whereby said door may be latched and unlatched in closed position by movements of said handle.

12. In a general service car having a movably mounted door, a handle mounted on said door and having relative sidewise and longitudinal movements with respect thereto, said door being manually closed by movement of said handle, means whereby said door may be latched and unlatched in closed position by movements of said handle, and other means for locking said door in closed position and which moves the handle into an unlatched position.

Signed at Chicago, Illinois, this 18th day of February, 1919.

HARRY S. HART.
